FIRE ALARM MECHANISM

Robert B. Shryock, Arlington, Tex.

Application August 11, 1933, Serial No. 684,660

1 Claim. (Cl. 177—355)

This invention relates to electric fire alarm systems and to heat-actuated devices for the operation of automatic fire alarms of that class which may employ a plurality of such devices at various points throughout a building or the like, and one of my general objects is to produce a device of this character which has a minimum number of contact points to lessen the possibility of corrosion with the result that the alarm system might fail in time of need.

Another object of the invention is to provide a thermostatic device with no moving wires subject to abrasion and electrical shorting, and in which the thermostatic mechanism is not in electric circuit with any part of the system or mechanism.

A further object of the invention is to provide a fire alarm system with means for the preliminary sounding of a local alarm when the heat reaches a predetermined point, and which, will sound a second alarm if the heat passes above the local alarm operation temperature.

A still further object of the invention is to produce a double circuit alarm of the character mentioned which is provided with visual signaling or annunciating mechanism to locate the particular protective device which has caused the sounding of the local alarm, and a device which may be used to effect a distant alarm as through a telephone line by the shorting thereof, but in which a temporary suspension of the current flow in the power line of the signal circuit will not turn in a false alarm on the telephone or external alarm circuit.

With the general objects named in view and others as will hereinafter appear, the invention consists in certain novel and useful features of construction and combinations of parts as hereinafter described; and in order that it may be fully understood, reference is to be had to the accompanying drawings, in which:—

Figure 1 is a plan view of a unit of the electrical fire alarm system embodying the invention, the cover of the unit being omitted.

Figure 2 is a section of the unit, including the cover, on the line II—II of Figure 1.

Figure 3 is an inverted plan view of the unit.

Figure 4 is a section on the line IV—IV of Figure 1.

Figure 5 is a detail perspective view of the thermostatic unit.

Figure 6 is a detail perspective view of a terminal support of the unit.

Figure 7 is a diagrammatic view of the pre-

furred alarm system as including two units connected in series.

Figure 8 is a diagrammatic view of a modified alarm circuit system.

In the said drawings, where like reference characters identify corresponding parts in all of the figures, the heat-actuated device is here shown as in the form of a coiled thermostat element 1, which has one of its ends clamped by a plate 2 to an upstanding leg 3 formed on a plate 10 4. The plate 4 is swivelled as at 5 on a base or support plate 6, having a cavity or space on its underside to house certain wiring hereinafter mentioned. The plate 6 forms the base of the protective device and may be secured to a wall, 15 placed on a shelf, or otherwise located at the point where there is a fire hazard. The swivelled plate 4 is provided with a projecting manual operating ear or handle 7 by means of which the plate may be adjusted to the position desired as 20 indicated by point 8 on the plate in cooperative relation with a series of temperature indicating marks 9 on the base 6. After the plate 4, and consequently the thermostat, has been adjusted, it is locked by a clamp bolt 10 carried by the base 25 6 and projecting through an arcuate slot 11 in the plate 4.

Secured to or projecting from the base 6 is a fixed ear 12, to the upper end of which and insulated therefrom, are three spring conducting 30 fingers or arms, 13, 14 and 15.

Also secured to or projecting from the base 6 is a second fixed ear or arm 16, as illustrated, having slots 16a receiving clamping bolts so that the arm is adjustable on the base. Secured to the 35 upper end of the arm and insulated therefrom are a pair of terminal members 17 and 18, the former, for contact with the spring finger 13, and the latter, for cooperation with the finger 15 as will hereinafter appear. In the construction here illustrated the terminal 17 is adjustable on the base 6 as explained, and the terminal 18 is provided with a compensating adjustable bolt contact 19 against which the finger 15 is normally in contact, the adjustment being provided to vary the time of a secondary alarm signal and to compensate for the setting of the terminal 17 with respect to the operating temperature of the thermostat as will hereinafter more particularly appear.

The third spring finger 14 is also subject to adjustment for time and to compensate for the setting of terminal 17, and is, therefore, normally in contact with an adjustable bolt 20 carried by an ear 21 projecting from the stand. 55

ard 16, and as this bolt and standard are not in electrical circuit it is unnecessary that they be insulated from the base 6.

The base 6 is provided with the following electrical connections; 22 is a binding post electrical-
ly connected by a wire 23 fitted within the hollow underside of the base 6, to the finger 13; 24 is a binding post electrically connected by a wire 25 to the spring finger 15; 26 is a binding post 10 electrically connected by a wire 27, to the spring finger 14; 28 is a binding post electrically connected by a wire 29, to the terminal 17; and 30 is a binding post electrically connected by a wire 31, to the terminal 18.

15 The thermostatic element 1 has its free end terminating in a head 32, and when set in the manner above described, the spring finger 13 is in the path of movement of said head 32 as the thermostat expands and moves, due to a tem-
20 perature rise. If the spring thermostat expands to a sufficient degree its head 32 will contact the finger 13 and will break the contact between said finger and its terminal 17. Said spring finger 13 is formed with a side ear 33 provided with a 25 contact point 34 for cooperative engagement and circuit closing, through a similar contact 35 car-
ried by the finger 14. Therefore, concurrently with the break of the contact between finger 13 and terminal 17, or a little thereafter as deter-
30 mined by the setting of the adjusting device 20, provided the thermostat continues to expand, contact points 34 and 35 will come into abutment to close a circuit therethrough.

In addition to the contact 34, the spring finger 35 13 carries a projecting post member 36 in po-
sition for contact with an insulating block 36a on the third spring finger 15. Therefore, fur-
ther continued movement of the thermostat 1 and spring finger 13, the extent of movement re-
40 quired and consequently the temperature which must be reached, being determined by the setting of the adjusting device 19, will ultimately cause the post 36 to move the spring finger 15 out of electrical connection with the terminal 18 through the bolt 19.

45 From the above, it will be evident that there is only one circuit established by the devices described, that made by contacts 34 and 35, while two circuits are broken by movement of such mechanism.

50 In Figure 7, the preferred method of connecting the devices is shown, a pair of the devices being indicated connected in series, although it is to be understood that any number may be employed each located at a point to be protected. In the drawings 75 and 76, respectively indicate the high and low voltage sides of a transformer, the former being connected to an electric light circuit or other source of power.

60 Extending from the low voltage winding of the transformer are a pair of power or lead wires 77 and 78. Connected to the wire 77 by a wire 79 are the binding posts 22 and 24 of the first protective device, the outlet binding posts 28 and 65 30, respectively, of said first protective device are connected by wires 80 and 81 to the binding posts 22 and 24 of the second protective device, and so on, throughout the entire series of devices, which are located at various points.

70 The middle outlet binding posts 26 of the devices are respectively connected by wires 82 and 83 to individual annunciators 84 and 85, located at a convenient point to indicate which protective device is in operation. The opposite terminals of 75 76 the annunciators are connected by wire 86 back

to the line or power wire 78 to complete the circuit.

The binding post 28 of the last protective de-
vice of a series is connected by a wire 87 to one 5 side of the coil of a relay 88, the other terminal of said coil being connected by wire 89 to the wire 78 from the transformer. This relay is of that character where the relay circuit is held open as long as the relay coil is energized. The terminals of the relay circuit are respectively connected by wires 90 and 91, to the power wire 77 and to a local alarm 92, the circuit being completed through wire 93 to the power wire 78. It will thus be evident that if current ceases to flow in the relay coil, the alarm 92 will be sounded through the breaking of the circuit through finger 13 and its terminal 17.

The binding post 30 of the final protective device of the series is connected by a wire 94 to one terminal of the coil of a relay 95, the other terminal of the coil having wire 96 leading to the power 20 wire 78. This relay is also of the type where the flow of current in the coil holds the relay circuit open. This relay is to operate any suitable outside alarm circuit, if the finger 15 breaks the circuit through its terminal 18. In the drawings, two 25 types of external alarm circuits are shown, one being energized from the transformer coil 16, and the other having its own source of power supply. The latter, the self-energized circuit, comprises a wire 97 connected to a battery 98, which in turn 30 is connected to any suitable type of alarm 99, the companion terminal of the alarm leading back through wire 100 to the other side of the relay. The other type of signal circuit constitutes wire 101 from one of the relay terminals, an alarm 35 102, a wire 103 to the line wire 78, and a line 104 from line wire 77, to the other terminal of the relay. Thus, upon the closing of these circuits, through the breaking of current flow through coil 95, the alarms 99 and 102 will both be operated. 40

To avoid the sounding of false alarms should the electric light or other current supply connected to winding 75, fail from any cause, the following stand-by power connections are provided: A wire 105 leads from the power wire 45 77 to one terminal of a relay coil 106, the other terminal being connected back to the power source, wire 78, by a wire 107. As long as current is flowing through the relay it is held against closing of the relay circuit. Also connected to the 50 wire 77 through wires 108 and 105 is a battery 109, the other side of the battery being connected by wire 110 to one terminal of the relay, the companion relay terminal being connected by wire 111 to the line wire 78. With these connections, it 55 will be evident that if the electric light circuit fails from any cause, the stand-by circuit will immediately feed the protective devices from the battery 109, before the inertia of the various parts has an opportunity to effect completion of 60 any of the alarm circuits, which, under the conditions mentioned, would otherwise cause the sounding of a false alarm.

Another method of connecting the devices is shown in Figure 8, where the electric light voltage 65 may be employed for operation of the alarms. In said figure, where a pair of devices are also shown as being connected in series, it being understood that any number of devices may be used, 70 77 indicates a transformer connected to a power or line wire 38. One terminal 39 of the low voltage side of the transformer 77 is connected by a wire 40 to binding posts 22 and 24 of the first protective device, and the binding posts 28 and 30 of said device are respectively connected to bind- 75

ing posts 22 and 24 of the second device, and so on throughout an entire series of any desired number, located at different points, within a building or location in which warning of fire is 5 to be sounded or indicated.

The terminal 26 of each protective device is connected by an individual wire 41 to a predetermined annunciator or visual signal 42 and 43, for the first and second protective devices 10 respectively herein illustrated. The opposite sides of the annunciator signals are connected by a common wire 44 to the other terminal 45 of the low side of the transformer.

The binding post 28 of the final protective device in the series, is connected by a wire 46 to one side of the coil of a relay 47 of that type in which a current flow prevents operation of the relay to close the second or relay circuit, and the other terminal of the said coil is connected by a wire 48 to the terminal 45 of the low side of the transformer. If desired, a pilot light 49 may be shunted across the coil of the relay to visually indicate that current is flowing through the protective devices.

One terminal of the open side of the relay 55 is connected by a wire 58 to one terminal of the coil of a third relay 59, while the other terminals of the two relays are connected by wires 60 and 61 to the power line. This third relay is of the 30 type requiring that a current shall flow through it before it will close or short its relay circuit, as represented by wires 62, for the operation of a telephone line alarm, a distant siren, or other type of signal.

With the constructions described, it will be evident that upon expansion of the thermostat to break the circuit at 13 and 17, relay 47 will be immediately affected and a circuit will close 40 through the alarm 52, which may be a local alarm. Simultaneously or slightly after the alarm is sounded (depending on the setting of bolt 19), contacts 34 and 35 will close a circuit through

the annunciator of the particular protective device which is being subjected to heat.

If the temperature at the protective device continues to rise, further expansion of the thermostat will cause the spring finger 13 through its 5 post 36 to strike the finger 15 and open the circuit between said finger and its terminal 18. This will cause the operation of the relay 55 to close a circuit through the third relay 59, which in turn 10 will close a circuit through the external alarm 10 wires 62.

With the apparatus and wire systems shown, it is possible to wire any desired number of devices in series and have a constant check on the operativeness of the system, in the first circuit 15 because of the auxiliary power source, and in the second by the pilot lights. From the above description it will be apparent that I have produced a system and apparatus which possesses all of the features of advantage set forth as desirable; and 20 while I have described and illustrated what appears to be the preferred forms of the invention, I reserve the right to make all changes within the spirit of the invention and without the ambit of the prior art.

I claim:—

In an electric fire alarm system, an electric current supply line, a pair of relays, a pair of conductors in circuit with the supply line and relays respectively, a third conductor, an annunciator in electrical connection with said third conductor and the supply line, a heat-responsive device for automatically breaking connection of one of said pair of conductors with the supply line and then establishing contact between said conductor and the third conductor to complete a circuit through the annunciator for then breaking the circuit through the second of said pair of conductors, and an alarm device in circuit with each of said relays to be successively actuated upon the breaking of the circuit through their respective relays.

ROBERT B. SHRYOCK.
